UNITED STATES PATENT OFFICE

106,178

DESIGN FOR AN OVERSHOE

George H. Bingham, Jr., Cambridge, Mass.

Application June 19, 1937, Serial No. 69,929

Term of patent 3½ years

To all whom it may concern:

Be it known that I, George H. Bingham, Jr., a citizen of the United States, residing at Cambridge, in the county of Middlesex and Commonwealth of Massachusetts, have invented a new, original, and ornamental Design for an Overshoe, of which the following is a specification, reference being had to the accompanying drawing, forming a part thereof.

In the drawing:

Fig. 1 is a side elevation of an overshoe, slightly in perspective, with the flap closed, showing my new design; and

Fig. 2 is a similar view, in diagrammatic outline, but showing the flap open.

I claim:

The ornamental design for an overshoe, substantially as shown and described.

GEORGE H. BINGHAM, JR.
